CLAIM

The ornamental design for a display panel portion with an animated graphical user interface, substantially as shown and described.

DESCRIPTION

FIG. 1 is a front view of a portion of a display panel, showing a first image of an embodiment of an animated computer icon; and,

FIG. 2 is a front view of the portion of the display panel, showing a second image of the embodiment of the animated computer icon.

The graphical user interface transitions sequentially among the images shown in FIGS. 1 and 2. The process or period in which one image transitions to another, forms no part of the claimed design.

The broken lines in the drawings illustrate portions of the display panel and its animated graphical user interface that form no part of the claimed design.
